UNITED STATES PATENT OFFICE.

BENJAMIN H. SOUTHLAND, OF SHERMAN, CALIFORNIA, ASSIGNOR OF ONE-HALF TO
EARL J. WILLIAMS, OF SHERMAN, CALIFORNIA.

WIRE-STRETCHER.

1,242,063.

Specification of Letters Patent.

Patented Oct. 2, 1917.

Application filed April 27, 1915. Serial No. 24,289.

To all whom it may concern:

Be it known that I, BENJAMIN H. SOUTHLAND, a citizen of the United States, residing at Sherman, in the county of Los Angeles 5 and State of California, have invented new and useful Improvements in Wire-Stretchers, of which the following is a specification.

This invention relates to wire stretchers 10 of that class which are adapted particularly for stretching or tensioning trolley wires and the like which require to be placed under heavy tension, and it has particular reference to an improved wire clamp which 15 will engage and hold the wire positively against slipping without bending, kinking or otherwise injuring the wire.

A further object of the invention is to 20 produce a wedge clamp which will operate smoothly and without undue friction so far as engagement with the wire is concerned and which may be very readily applied and detached, as may be required.

A further object of the invention is to 25 produce a clamp of the character described which will be simple in construction, inexpensive, and capable of resisting any strain to which it may be subjected.

With these and other ends in view which 30 will readily appear as the nature of the invention is better understood, the same consists in the improved construction and novel arrangement and combination of parts which will be hereinafter fully described and 35 particularly pointed out in the claims.

In the accompanying drawings has been 40 illustrated a simple and preferred form of the invention, it being, however, understood that no limitation is necessarily made to the precise structural details therein exhibited, but that changes, alterations and modifications within the scope of the claims may be 45 resorted to when desired.

In the drawings:—

45 Figure 1 is a view in front elevation of the improved clamp.

Fig. 2 is a rear elevation of the same.

Fig. 3 is a transverse sectional view taken on the line 3—3 in Fig. 1.

50 Fig. 4 is a front view showing the clamp with the face plate detached.

Fig. 5 is a front view showing the body member of the clamp with the face plate and the wedge detached.

Fig. 6 is a rear view showing the wedge 55 detached.

Fig. 7 is a sectional view taken on the line 7—7 in Fig. 3.

Corresponding parts in the several figures are denoted by like characters of reference. 60

The body member of the improved clamp consists of a plate or casting 15 of oblong shape having in its front face a recess 16 producing along the upper portion of said body member an overhanging flange 17 and 65 along the lower portion a shoulder or offset 18. Said shoulder, which defines the lower wall of the recess 16, is inclined with reference to the flange 17, the recess 15 being of tapering form, as shown. The bottom of 70 the recess is provided with a longitudinal groove 19 which is formed in parallel relation to the lower wall of the recess and at no great distance therefrom. The shoulder defining the lower wall of the recess is provided 75 intermediate its ends with a recess or cavity 20. The body member is formed on its rearward side with a longitudinally disposed inclined reinforcing rib coinciding with the groove 19 so that said body member will not be materially weakened by the formation of said groove. The body member is also formed with additional vertically disposed reinforcing ribs whereby it is enabled to resist extremely heavy strains. 80

23 designates a wedge which is positioned in the recess 16, said wedge having a smooth lower edge face 24 riding upon the shoulder or offset 18 which is likewise perfectly smooth. Friction between said offset and 90 the wedge may be further reduced by the use of proper lubricant for the reception of which the recess 20 is provided. The opposed wire engaging faces of the wedge 23 and the overhanging flange 17 are slightly 95 arcuate so that a wire may be effectively gripped therebetween; the engaging face 25 of the wedge is perfectly smooth, while the engaging face 26 of the flange 17 is roughened, as best seen in Fig. 7, in order to take 100 a firm grip and hold on the wire. The small end of the wedge is formed with an eye 27 with which is connected a link 28, whereby connection may be made with the tackle or other means that is utilized for pulling the 105 wire in order to tension the same. The end of the wedge having the eye 27 is also built up or reinforced to form an anvil 29 which,

if the wedge should become stuck, may be struck with the hammer for the purpose of disengaging the parts without injury.

The body member 15 is provided with 5 apertures 30 for the passage of fastening members, such as bolts 31, whereby a face plate 32 is secured in position, the upper edge of said face plate being spaced from the overhanging flange 17 so as to offer no 10 obstruction to the engagement of the clamp with the wire that is to be tensioned.

The wedge 24 is provided on its rear face with a rib or projection 33 which is positioned in parallel relation to the lower edge 15 of said wedge and which engages the longitudinal groove 19 in the body member, said groove and rib being preferably of rectangular cross section, as shown. When the parts of the device are assembled the rib traveling 20 in the groove serves to guide the wedge and to prevent either end of the wedge from tipping or tilting upwardly, parallel relation being thus maintained between the opposed wire engaging faces of the wedge and the 25 flange 17. The rib also serves to direct the end of the wedge formed with the eye 27, in contact with the body member, and limit the movement of the wedge in one direction.

In the use of the improved device, the 30 wire, cable or other object that is to be stretched or tensioned, is inserted between the opposed faces of the wedge 24 and the flange 17, the wedge being meanwhile positioned at the lower limit of its movement. 35 By pulling the wedge upwardly with respect to the inclined shoulder 18, the wire will be gripped between the engaging faces 25 and 26, the face 25 of the wedge sliding smoothly over the wire, while the roughened 40 surface of the face 26 will prevent the body member from slipping along the wire. Increased pulling strain upon the wedge will serve to proportionately tighten the grip upon the wire, the pulling strain being applied by means of tackle of any description. 45 The construction of the device is of such a nature that a very heavy pulling strain may

be employed without danger of buckling or distorting the clamp and without injury to the wire that is being stretched. When the 50 wire is to be released the wedge will usually let go thereof without difficulty when the pulling strain is interrupted; should it become stuck, however, a tap with a hammer on the reinforced eye portion of the wedge 55 will quickly release and let go of the wire.

Having thus described the invention, what is claimed as new, is:

1. A device of the class described comprising a body member having in its front face a longitudinal tapered recess producing an overhanging flange and a shoulder disposed convergently with respect to said flange, the bottom of the recess having a longitudinal groove which is parallel to the 65 shoulder, in combination with a wedge positioned in said recess and having a longitudinal rib engaging the groove, the opposed faces of the wedge and the overhanging flange being in parallel relation, and a 70 removable face plate secured on the bottom member to retain the wedge against lateral displacement.

2. In a device of the class described, a body member having a recess producing an 75 overhanging flange and a shoulder disposed convergently with relation thereto, a wedge slidably guided on said shoulder with its upper face in parallel relation to the overhanging flange, said wedge having at its 80 narrow end an offset forming a shoulder in which is formed an eye and a projection constituting an anvil, a rib formed on said wedge slidably in a slot formed in the body member whereby the shoulder is caused to 85 engage the body member to limit its movement in one direction and a face plate secured on the body member to assemble the wedge therewith.

In testimony whereof I affix my signature. 90

BENJAMIN H. SOUTHLAND.

Witness:
HELEN J. POWELL.
